No. 626,701

Patented June 13, 1899.

E. D. HOAG.

BAG HOLDER.

(Application filed Apr. 8, 1898.)

(No Model.)

UNITED STATES PATENT OFFICE.

ELWYN D. HOAG, OF CHARLES CITY, IOWA, ASSIGNOR OF ONE-HALF TO
CHARLES P. GORDON, OF SAME PLACE.

BAG-HOLDER.

SPECIFICATION forming part of Letters Patent No. 626,701, dated June 13, 1899.

Application filed April 6, 1898. Serial No. 676,655. (No model.)

To all whom it may concern:

Be it known that I, ELWYN D. HOAG, a citizen of the United States, residing at Charles City, in the county of Floyd and State of Iowa, have invented a new and useful Bag-Holder, of which the following is a specification.

My invention relates to devices for holding bags to be filled, and has for its object to furnish a device of this class provided with means for raising the mouth of the bag and shaking down the contents during the operation of filling.

With this object in view my invention consists in a bag-holder comprising a stand with a fixed upright thereon, a cross-bar mounted to slide upon the upright and be held in any position thereon, means for suspending the bag carried by said upright, and devices for elevating the cross-bar and bag-holding mechanism actuated by the operation of a treadle.

My invention further consists in the improved construction, arrangement, and combination of parts hereinafter fully described and afterward specifically pointed out in the appended claims.

In order to enable others skilled in the art to which my invention most nearly appertains to make and use the same, I will now proceed to describe its construction and operation, reference being had to the accompanying drawings, forming part of this specification, in which—

Figure 1 is a perspective view illustrating a bag-holder constructed in accordance with my invention with a bag suspended thereon. Fig. 2 is a view of the holder in front elevation. Fig. 3 is a transverse sectional view on the plane indicated by the broken line 3 3 of Fig. 2, looking downward. Fig. 4 is a vertical sectional view on a plane cutting through the holder from front to rear on the line 4 4 of Fig. 2, a portion of the base-board being broken away. Fig. 5 is a transverse sectional view on the plane indicated by the broken line 5 5 of Fig. 2. Fig. 6 is a detail view, being a vertical section on the line 6 6 of Fig. 4. Fig. 7 is a view similar to Fig. 4, illustrating a slightly-modified form of my invention in which the treadle and hoisting mechanism are attached to the rear instead of the front of the upright.

Like numerals mark the same parts wherever they occur in the various figures of the drawings.

Referring to the drawings by numerals, 10 55 indicates a base-board properly supported from casters or rollers 11 in order that it may be easily moved from place to place.

12 indicates an upright erected at the rear side or end of the base-board and carried to 60 a suitable height to permit of bags of all the lengths in general use being suspended from a cross-bar 13, mounted to slide vertically thereon. The cross-bar 13 is provided with a metallic loop or staple 14, which passes 65 around the upright 12 and is prevented from being raised off the top of the upright by means of a stop-pin 15.

The bag-holder proper is composed of wire, the straight portion 16 thereof being secured 70 on top of the cross-bar 13 by staples or eyes 17, the wire being bent horizontally at each end and formed into coils 18, the wire after passing the coils extending to a distance from the cross-bar sufficient to distend the mouth 75 of any ordinary bag or sack. At these points 19 the wire is again turned back to points 20 on the top of the cross-bar, when it is again carried forward and downward through eyes 21, secured in the front face of the cross-bar, 80 from whence it is again carried upward and bent backward above the cross-bar, forming points 22. A wire yoke 23, substantially V-shaped, has its upper ends bent horizontally and passed through eyes 24, depending from 85 the bottom of the cross-bar 13. Suspended from the center of the yoke 23 is an eyebolt 25, which passes through eyes 26 and 27, secured to the front of the upright 12.

28 indicates a treadle pivoted on a pin 29, 90 projecting from a supplementary upright 30 by the side of the main upright 12. The inner end of the treadle is pivotally secured at the lower end of a rod 31, which is bent near its upper end to a horizontal position, as at 32, 95 where it is passed through an eye in an arm 33, projecting laterally from a ring 34, mounted upon the eyebolt 25 between the eyes 26 and 27. After passing through the eye in the arm 33 the rod 31 is again bent upward at 35 and 100 horizontally at 36, the horizontal arm 36 passing between the eyebolt 25 and the upright 12.

In the modification shown in Fig. 7 the yoke 23 straddles the upright 12, and the eyes 26 and 27, the eyebolt 25, the treadle, the rod 31, the ring 34, and its arm 33 are all mounted 5 in the rear instead of in the front of the standard 12. For many purposes this will be the preferred form, for the reason that there will be no liability of the bag becoming hung or entangled on any of the moving parts.

10 The construction of my invention will be readily understood from the foregoing description, and its operation may be described as follows: A bag to be filled is placed in position in front of the upright to have its bottom 15 rest upon the base-board 10, the mouth of the bag being stretched around the wire holder and the material impaled upon the points 22. The grain or other filling may now be poured into the bag out of measures or with scoop- 20 shovels until the bag is partially filled, when by pressing downward upon the treadle 28 the rod 31 will be forced upward, carrying the arm 33 and the ring 34 with it, until the horizontal arm 36 strikes the under side of the eye 25 26. During this operation the ring 34 binds upon the eyebolt 25 and carries the eyebolt, the yoke 23, the cross-bar 13, and the wire bag-holder, with the bag suspended thereon, also upward. When this limit of the upward 30 movement is reached, the treadle is released and the ring 34 slides down on the eyebolt 25 until it rests on the eye 27. In the meantime, however, the weight of the bag being centered at a distance in front of the upright 35 12 upon the wire holder will have a tendency to press the cross-bar 13 against the front of the upright and the loop 14 against the back thereof, thus causing the loop and cross-bar to bind on the upright and prevent the cross- 40 bar from descending with the ring 34. A repetition of this movement of the treadle will still further elevate the cross-bar and wire bag-holder until the limit is reached and the loop 14 strikes the stop-pin 15.

45 With the construction shown in Fig. 7 the operation of the various parts is identically the same.

The advantages attending the use of my invention will be obvious from the foregoing description. The bag, no matter what its length 50 within the limit of the height of the upright, may be entirely suspended off the base-board, so that the contents will fall to the bottom;

and it may be let down at any time by lifting the points 19 of the bag-holder, which will relieve the pressure of the cross-bar 13 and loop 14 on the front and rear of the upright. The arrangement of mechanism is such that a bag with considerable weight of material in it can be raised very readily and when filled can be 60 as readily dropped upon the base-board to be tied and removed therefrom.

While I have illustrated and described the best means for carrying out my invention, I do not wish to be understood as restricting myself to the exact details of construction shown; but hold that any slight changes or variations such as might suggest themselves to the ordinary mechanic would properly fall within the limit and scope of my invention. 70

Having thus fully described my invention, what I claim as new, and desire to secure by Letters Patent of the United States, is—

1. The combination with the upright and the cross-bar carrying the bag-holder and provided with means for holding it in any position to which it may be raised on the upright, of the yoke, 23, pivotally connected to the under side of the cross-bar, the eyebolt or rod mounted in eyes projecting from the upright 80 and pivotally connected to the lower end of the yoke, and means for giving a step-by-step, vertical movement to the eyebolt, substantially as described.

2. The combination with the upright, the wire bag-holder thereon and the loop secured to the top of the cross-bar and encircling the upright, of the yoke pivoted to the under side of the cross-bar, the eyebolt or rod pivotally connected to the yoke and mounted in eyes 90 projecting from the upright, the ring, 34, mounted upon the eyebolt or rod, between its supporting-eyes and provided with the laterally-projecting arm having a horizontal eye, the pivoted treadle, and the rod, pivotally connected to the inner end of the treadle, passing through the horizontal eye of the ring-arm and bent horizontally at its upper end to form a stop-arm adapted to limit the upward movement of the devices, substantially as described. 100

ELWYN D. HOAG.
